DESIGN FOR A COMPACT

Edmond Foret, New York, N. Y., assignor to Cartier, Inc., New York, N. Y., a corporation of
New York

Application November 15, 1941, Serial No. 104,165

Term of patent 7 years

To all whom it may concern:

Be it known that I, Edmond Foret, a citizen of France, residing at New York city, in the county and State of New York, have invented a new, original, and ornamental Design for a Compact, of which the following is a specification, reference being had to the accompanying drawing, forming part thereof.

I claim:

The ornamental design for a compact, as shown.

EDMOND FORET.
